UNITED STATES PATENT OFFICE

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY

LEVELING MACHINE

Application filed April 7, 1928. Serial No. 268,355.

This invention relates to machines for use in the manufacture of boots and shoes (herein referred to generally as shoes) for performing what is commonly termed the leveling operation, and more particularly to machines of that type in which a leveling tool, for example a spring-pressed roll operates to apply its pressure to different portions of the bottom of the shoe successively in response to relative movement of the tool and the shoe lengthwise of the shoe. While such machines are used principally for treating the outsoles of shoes, they are also sometimes used to prepare the lasted shoe for the reception of the outsole, and the term "leveling" is, accordingly, employed herein in a general sense to comprehend such different uses.

The bottom of a shoe usually presents rearwardly of the ball-line a substantial lengthwise slope relative to the forepart, which is especially pronounced in shoes having high-arched shanks. Accordingly, as the shoe is positioned bottom upward in machines of the above-mentioned type, there is a substantial variation in the height at which different portions of the shoe bottom are presented to the leveling roll and also in the angular relation between the longitudinal contour of different portions of the bottom face and the direction of the pressure applied by the roll. In view of these conditions, such machines have been commonly provided heretofore with pressure-controlling means associated with the spring-pressed roll, both to compensate for the differences in height, and also, by suitable relief of the pressure in operating immediately at the rear of the ball-line, to prevent the roll from dropping too forcibly down the slope from the ball into the shank or from bearing too hard on the shoe bottom in returning from the shank to the forepart with consequent danger of damage to the shoe or to the last.

The present invention deals in a different manner with the conditions thus encountered, 45 through the provision of a novel organiza-

tion of means for controlling the relation between the leveling tool and the shoe. In one novel aspect of the invention, there is thus provided means whereby different portions of the bottom of the shoe, such as the forepart and the shank, are presented at substantially the same height for the action of the leveling tool, while in another novel and important aspect there is means for controlling the relation between the shoe and the tool in such manner as to maintain substantially the same angular relation, for example, a substantially perpendicular relation, between the direction of the pressure applied by the tool and the longitudinal contour of different portions of the bottom of the shoe. For the accomplishment of the objects in view, the construction herein shown comprises mechanism which operates in suitable time relation to the relative movements of the leveling roll and the shoe lengthwise of the shoe to tip the shoe about an axis extending laterally thereof and thus to present the different portions of its bottom face in the desired relation to the roll. Preferably this axis is located substantially at the junction of the forepart and shank portions of the shoe bottom, and a tipping movement of the shoe takes place at the time when the roll is engaging the shoe in that location. In the cycle of operations of the illustrated machine there is a pause in the relative movement of the roll and the shoe lengthwise of the shoe when the roll, in traversing the shoe from the toe end rearwardly, is located substantially at the ball-line, and during this pause the shoe is tipped about the above-mentioned axis to bring the sloping portion of its bottom face at the rear of the ball-line up to substantially the same level as that in which the forepart was previously presented to the roll. As the operation of the machine continues, the roll then acts to apply to that portion of the bottom face pressure of substantially the same degree and in substantially the same angular relation to the lengthwise con-

tour of the shoe bottom as that previously applied to the forepart. Furthermore, as the operation of the roll progresses along the shank in the illustrated machine, the shoe is tipped gradually in the opposite direction from that of its first tipping movement to present different portions of the curved shank successively in substantially the same relation to the roll. Thereafter, in the traverse of the roll back to the toe end of the shoe, tipping movements are imparted to the shoe which are the reverse of those imparted to it in the traverse of the roll from the toe end rearwardly, so that the same conditions as to height of the shoe bottom and direction of pressure are maintained in the return to the toe.

It will be evident that the construction thus provided is especially well adapted to the application of a substantially uniform degree of pressure to all portions of the shoe bottom that are operated upon, since there is nothing in the manner of presentation of the shoe which tends to cause any substantial alteration in the stress of the pressure spring and for the further reason that there is no occasion to relieve the pressure in order to avoid damage by the action of the roll in entering or leaving the shank. It will further be understood that, since the shoe is so presented that the direction of the pressure applied by the roll is in substantially perpendicular relation to the longitudinal contour of the shoe bottom both at the forepart and at the rear of the ball-line, the pressure is applied in the most effective manner for the purposes in view and without danger at any portion of the shoe bottom of objectionable drag on the sole in the direction of its length.

The different features of the invention, including various novel details of construction and combinations of parts, will now be more particularly described by reference to the accompanying drawings and thereafter pointed out in the claims.

In the drawings,

Fig. 1 is a view in side elevation, with parts broken away, showing a machine in which the invention is embodied; and

Figs. 2, 3, 4 and 5 are views illustrating different positions of the shoe in relation to the leveling roll in the cycle of operations of the machine.

For purposes of illustration the invention is herein shown as embodied in a machine of a comparatively simple type, although it is to be understood that it is susceptible of various embodiments. The machine is provided with a leveling roll 10 mounted for turning movement on a roll carrier 12, this carrier being pivotally mounted at 14 on a holder 16 which is fast on a shaft 18 mounted in bearings 20 on the frame of the machine for turning movement about an axis at right angles to the axis 14 of the carrier 12. The roll 10 is arranged to en-

gage the bottom of a shoe *a* (herein shown diagrammatically) which is supported by means hereinafter described, and for pressing the roll downwardly on the bottom of the shoe there is provided a spring 22 which bears at one end on an arm 24 of the holder 16 and at its opposite end on an arm 26 which projects upwardly from the carrier 12. A rod 28 which is pivoted at 30 on the arm 24 extends through the spring 22 and loosely through an opening in the arm 26, and has threaded thereon at its outer end a hand wheel 32 which is adapted to serve adjustably as an abutment for engagement with the arm 26 to limit downward movement of the roll in case no shoe is mounted in the machine. A nut 34 is provided for clamping the hand wheel 32 in adjusted position.

It will be understood that the shaft 18 serves as means whereby the roll may be tipped laterally of the shoe to any desired extent and in any desired relation to the cycle of relative movements of the roll and the shoe lengthwise of the shoe for operation along the side edges of the shoe bottom, especially in the shank. For effecting such tipping movements of the roll, as well as other movements hereinafter described, there is secured on a shaft 36 a cam wheel 38 having in its periphery a path cam 40 in which is mounted a roll 42 carried by a lever arm 44 pivoted at its lower end on the frame of the machine. At its upper end the arm 44 is provided with a slot 46 in which is adjustably secured a stud 48 which carries a roll 50 positioned in a slot 52 formed in an arm 54 which is fast on the shaft 18. It will be understood that the cam 40 is so shaped as to impart to the roll the desired tipping movements in time relation to the other movements of the machine, and that by adjustment of the stud 48 in the slot 46 of the arm 44 the amplitude of such tipping movements may be varied.

For positioning the shoe in proper relation to the roll 10 the machine is provided with a shoe support comprising an arm 56 pivotally mounted at its lower end at 58 on the frame, and pivotally mounted by means of a spindle 60 on the upper end of the arm 56 is a shoe holder comprising a depending arm 62 fast on the spindle 60. The arm 62 has in one side thereof a guideway in which is adjustably mounted for upward or downward movement a block 64 having at its lower end a lateral extension 66 provided with a guideway 67 in which are mounted a heel post 68 for supporting the heel end of the last and shoe and a toe post 70 for supporting the toe end of the shoe. A spindle 72 threaded in the lower end of the arm 62 is arranged to bear at one end on the lower face of the extension 66 of the block 64 and serves by adjustment to determine the height at which the shoe as a whole is positioned on

the shoe support. Swivelled in a bearing formed in the block 64 is a spindle 74 which is provided with right and left-hand threaded portions for engagement respectively with corresponding threads formed in the shoe-supporting members 68 and 70, this spindle serving by adjustment to move these members equally toward or from each other to adapt them to receive shoes of different lengths. 5

10 The member 70 is provided at its upper end with a pad 76 for engaging the forepart of the shoe, and has also mounted thereon a roll receiver 78 for guiding the roll 10 on and off the toe end of the shoe without damage to the 15 shoe.

For imparting movements to the shoe support to cause the roll 10 to traverse the bottom of the shoe, there is connected to the arm 56 a link 80 provided with a roll 82 which 20 lies in a path cam 84 formed in one side of the cam wheel 38. That end of the link 80 which carries the roll 82 is supported on the upper end of an arm 86 which is pivotally mounted on a spindle 88 on the frame of the 25 machine. At its other end the link 80 carries a pin 90 which extends through a slot 92 in the arm 56 and is connected by a link 94 to a lever arm 96 fast on a spindle 98 which also carries a hand lever 100. It will thus 30 be seen that by movement of the lever 100 the position of the pin 90 in the slot 92 may be varied, and by this means a variation may be effected in the amplitude of movement of the shoe support in adapting the machine to 35 operate on shoes of different lengths. A latch 102 mounted on the lever 100 serves in co-operation with notches 104 formed in a fixed segmental member 106 to hold the lever 100 in adjusted position.

40 For effecting and controlling movements of the shoe holder 62 about the axis of the spindle 60 for purposes of this invention, there is provided in the opposite side of the cam wheel 38 from the path cam 84 another 45 path cam 108 in which is mounted a roll 110 carried by an arm 112, this arm being pivotally mounted at its lower end on the spindle 88. The upper end of the arm 112 is connected by a link 114 to an arm 116 fast on 50 the spindle 60. It will thus be seen that through these connections swinging movements are imparted to the shoe holder 62 in predetermined time relation to the swinging movements of the shoe-supporting arm 56 55 controlled by the path cam 84. The link 114 is adjustably connected to the upper end of the arm 112 through the provision of a slot 118 in the arm, so that the amplitude of the swinging movements of the shoe holder may 60 be varied.

For imparting turning movement to the cam wheel 38 there is fast on the shaft 36 a worm gear 120 engaged by a worm 122 on a shaft 124. The shaft 124 is arranged to be 65 driven intermittently by a belt pulley 126

through a suitable clutch which may be of any convenient type, the construction shown comprising a clutch member 128 which is movable lengthwise of the shaft 124 and mounted to turn therewith, this clutch member being arranged to co-operate with a clutch member 130 fast on the pulley 126. The clutch member 128 is controlled by a bell-crank lever 132 having a pin-and-slot connection 134 with a lever 136 pivoted on the spindle 88. A spring plunger 138 is arranged to act on the lever 136 to hold the clutch member 128 normally in idle position. For actuating the clutch to start the machine there is provided a treadle lever 140 which is pivotally mounted on the spindle 88 and is normally held upraised by a spring 142, this lever upon its depression being arranged to engage a lug 144 on the lever 136 and thus to swing the latter in the direction to force the clutch member 128 into engagement with the member 130. When the lever 136 is in its idle position with the machine at rest, a lug 146 thereon is arranged to extend into a notch 148 formed in the periphery of the cam wheel 38. 50 When the treadle lever is depressed to start the machine, this lug is withdrawn from the notch 148, and thereafter it is engaged by the periphery of the cam wheel to hold the clutch member 128 in operative position until the machine has completed its cycle, whereupon the lug again enters the notch in response to the action of the spring plunger 138 simultaneously with the release of the clutch. 55

It will be seen that, as illustrated, the axis of the swinging movements of the shoe holder 62, coinciding with the axis of the spindle 60, extends laterally of the shoe in a location substantially at the junction of the forepart and shank portions of the shoe bottom, and it is preferable that this axis be positioned substantially or approximately in that relation to the shoe in the operation of the machine on different sizes and styles of shoes. Adjustment of the shoe holder to secure such a 60 relation in changing from one size or style of shoe to another is effected by use of the threaded spindles 72 and 74.

In the use of the machine the operator mounts a shoe on the shoe support when the parts are positioned as illustrated in Fig. 2, and then starts the machine by depressing the treadle 140. The machine then operates automatically in a predetermined cycle whereby, in the construction illustrated, there is effected a single reciprocation of the shoe support arm 56 about its axis 58 through the action of the cam 84 to cause the roll 10 to traverse the shoe from the toe end rearwardly to the heel-seat and then to return to the toe end, although it is to be understood that the invention is not limited to a construction in which the relative movements of the shoe and the roll lengthwise of the shoe are of this particular character. In the 65 70 75 80 85 90 95 100 105 110 115 120 125 130

course of the cycle of operations the roll is tipped by the action of the path cam 40 to incline it as desired for operating along the side edges of the shoe bottom. In time relation to the swinging movements of the shoe supporting arm 56, the shoe holder 62 is swung about the axis of the spindle 60 by the action of the cam 108 to tip the shoe lengthwise and thereby to control as desired the relation of different portions of its bottom face to the leveling roll. The cams 84 and 108 in the construction shown are so designed that the shoe holder 62 is maintained in approximately the same relation to the supporting arm 56 in the traverse of the roll from the toe end to the ball-line, whereupon there is a pause in the movement of the arm 56 during which the shoe holder is tipped by its cam 108 to bring that portion of the bottom face of the shoe which slopes rearwardly from the ball-line to substantially the same level as the forepart previously operated upon by the roll, as illustrated in Fig. 3. The swinging movement of the arm 56 is then resumed, causing the roll to traverse the shoe bottom from the ball-line rearwardly, and it will be seen that the direction of its pressure is substantially perpendicular to the longitudinal contour of that portion of the shoe bottom that slopes rearwardly from the ball-line, as it was previously to the longitudinal contour of the forepart. As the roll traverses the shank the cam 108 swings the shoe holder 62 progressively in the opposite direction from that in which it was swung when the roll was positioned at the ball-line, thus presenting different portions of the curved shank successively with their longitudinal contours in substantially the same angular relation to the direction of the pressure applied by the roll. In this manner the roll traverses the shank to the heel-seat, whereupon the direction of the movement of the arm 56 is reversed. As the roll traverses the shank in the opposite direction a tipping movement is imparted to the shoe holder in the opposite direction from that in which it was tipped in the rearward traverse of the roll along the shank, to maintain the relation between the roll and the longitudinal contour of the shank substantially the same as in the first operation of the roll thereon. When the roll again arrives at the ball-line there is a pause in the swinging movement of the arm 56, during which the shoe holder is swung to tip the shoe into the same relation to the roll as that which it occupied in the first operation of the roll on the forepart, and this relation is maintained until the roll leaves the toe end of the shoe.

It will thus be seen that there is provided a construction whereby the different portions of the shoe bottom are presented at substantially the same height for the action of the leveling roll thereon, so that the pressure ap-

plied by the roll in response to the action of the spring 22 is substantially constant in operating on different portions of the shoe bottom. It will be further observed that the shoe is so presented to the action of the roll that substantially the same angular relation, preferably a substantially or approximately perpendicular relation, is maintained between the longitudinal contour of the shoe bottom and the direction of the pressure applied by the roll in the operations on different portions of the shoe bottom including the curved shank. The pressure is thus applied to the different portions in a direct manner such as to secure the most satisfactory results, without danger of damage to any portion of the bottom of the shoe by drag of the roll thereon in a direction lengthwise of the shoe. 70 75 80

Having described the invention, what I claim as new and desire to secure by Letters Patent of the United States is:—

1. In a machine of the class described, a leveling tool, means for effecting relative movement of said tool and a shoe lengthwise of the shoe to cause the tool to traverse the forepart and shank portions of the bottom of the shoe, and means for maintaining the leveling pressure substantially constant on said different portions of the bottom of the shoe comprising mechanism for moving the shoe 90 95 to present the different portions at substantially the same height for the action of the leveling tool thereon.

2. In a machine of the class described, a leveling tool, means for effecting relative movement of said tool and a shoe lengthwise of the shoe to cause the tool to traverse the forepart and shank portions of the bottom of the shoe, and means for maintaining the leveling pressure substantially constant on said different portions of the bottom of the shoe comprising mechanism for tipping the shoe about an axis extending laterally thereof to present the different portions at substantially the same height for the action of the leveling tool thereon. 100 105 110

3. In a machine of the class described a leveling tool, means for effecting relative movement of said tool and a shoe lengthwise of the shoe to cause the tool to traverse the forepart and shank portions of the bottom of the shoe, and means for controlling the shoe to present said different portions of the shoe bottom with their longitudinal contours in substantially the same angular relation to the direction of the pressure applied by the tool. 115 120

4. In a machine of the class described, a leveling tool, means for effecting relative movement of said tool and a shoe lengthwise of the shoe to cause the tool to traverse the forepart and shank portions of the bottom of the shoe, and means for tipping the shoe about an axis extending laterally thereof to present said different portions of the bottom of the shoe at substantially the same height for the 125 130 135

- action of the tool thereon and with their longitudinal contours in substantially the same angular relation to the direction of the pressure applied by the tool.
5. In a leveling machine, a leveling tool, means for effecting relative movement of said tool and a shoe lengthwise of the shoe to cause the tool to traverse the bottom of the shoe, and means for tipping the shoe lengthwise in automatically determined time relation to said relative movement to present different portions of its bottom face with their longitudinal contours in substantially the same angular relation to the direction of the pressure applied by the tool.
6. In a leveling machine, a leveling tool, means for effecting relative movement of said tool and a shoe lengthwise of the shoe to cause the tool to traverse the bottom of the shoe, and means for tipping the shoe about an axis extending laterally thereof and located substantially at the junction of the forepart and shank portions of the shoe bottom to present said different portions of the shoe bottom with their longitudinal contours in substantially the same angular relation to the direction of the pressure applied by the tool.
7. In a machine of the class described, a leveling roll, means for effecting relative movement of said roll and a shoe lengthwise of the shoe to cause the roll to traverse the forepart and shank portions of the bottom of the shoe, and automatic means for controlling the shoe in time relation to said relative movement to present said different portions of the shoe bottom with their longitudinal contours in substantially perpendicular relation to the direction of the pressure applied by the roll.
8. In a machine of the class described, a leveling roll, means for effecting relative movement of said roll and a shoe lengthwise of the shoe to cause the roll to traverse the forepart and shank portions of the bottom of the shoe, and controlling means constructed to position the shoe with the longitudinal contour of its forepart in substantially perpendicular relation to the direction of the pressure applied by the roll and by tipping movement of the shoe to present that portion of its bottom face which slopes rearwardly from the ball-line also with its longitudinal contour in substantially perpendicular relation to the direction of the pressure at the time of the operation of the roll thereon.
9. In a leveling machine, a leveling roll, means for effecting relative movement of said roll and a shoe lengthwise of the shoe to cause the roll to traverse the forepart and shank portions of the shoe bottom successively, and means arranged to act when the roll is positioned at the ball of the shoe to tip the shoe about an axis extending laterally thereof to present that portion of its bottom face that slopes rearwardly from the ball-line at substantially the same level for the action of

the roll as the forepart previously operated upon.

10. In a leveling machine, a leveling roll, means for effecting relative movement of said roll and a shoe lengthwise of the shoe to cause the roll to traverse the forepart and shank portions of the shoe bottom successively, and means arranged to act when the roll is positioned at the ball of the shoe to tip the shoe about an axis extending laterally thereof and located substantially in the area of contact between the roll and the shoe to present that portion of the shoe bottom that slopes rearwardly from the ball-line with its longitudinal contour in substantially the same angular relation to the direction of the pressure applied by the roll as the longitudinal contour of the forepart previously operated upon.

11. In a leveling machine, a leveling roll, means for effecting relative movement of said roll and a shoe lengthwise of the shoe to cause the roll to traverse the forepart and shank portions of the shoe bottom, said means being so formed as to effect a pause in said relative movement when the roll is positioned at the ball of the shoe, and mechanism arranged to act at the time of said pause to tip the shoe about an axis extending laterally thereof for presenting that portion of its bottom face that slopes rearwardly from the ball-line in substantially the same relation to the roll as the forepart previously operated upon.

12. In a leveling machine, a leveling roll, means for effecting relative movement of said roll and a shoe lengthwise of the shoe to cause the roll to traverse the forepart and shank portions of the shoe bottom, said means being so formed as to effect a pause in said relative movement when the roll is positioned substantially at the junction of the forepart and shank portions of the shoe bottom, and mechanism arranged to act at the time of said pause to tip the shoe about an axis extending laterally thereof and located substantially in the area of contact between the roll and the shoe to elevate that portion of the bottom face of the shoe that slopes rearwardly from the ball-line and to present it with its longitudinal contour in substantially the same angular relation to the direction of the pressure applied by the roll as the longitudinal contour of the forepart previously operated upon.

13. In a leveling machine, a leveling tool, means for effecting relative movement of said tool and a shoe lengthwise of the shoe to cause the tool to traverse the bottom of the shoe, and means arranged to operate in time relation to said relative movement in the traverse of the tool from one end of the shoe toward the other end to tip the shoe first in one direction and then in the opposite direction about an axis extending laterally thereof to present different portions of its bottom face in substantially the same relation to the tool.

14. In a leveling machine, the leveling roll, means for effecting relative movement of said roll and a shoe lengthwise of the shoe to cause the roll to traverse the forepart and shank portions of the bottom of the shoe successively, and means arranged to operate when the roll is positioned substantially at the ball of the shoe to tip the shoe about an axis extending laterally thereof to present that portion of its bottom face that slopes rearwardly from the ball-line with its longitudinal contour in substantially the same angular relation to the direction of the pressure applied by the roll as the longitudinal contour of the forepart previously operated upon and thereafter to tip the shoe in the opposite direction as the roll traverses the shank toward the heel-seat. 70
15. In a leveling machine, a leveling roll, means for effecting relative movement of said roll and a shoe lengthwise of the shoe to cause the roll to traverse the forepart and shank portions of the bottom of the shoe successively, and automatic means for imparting to the shoe a tipping movement in one direction about an axis extending laterally thereof when the roll is positioned substantially at the ball of the shoe and for tipping it progressively in the opposite direction about said axis as the roll traverses the shank. 75
16. In a machine of the class described, a leveling roll, a shoe support, and means for effecting relative movement of said roll and support lengthwise of the shoe to cause the roll to traverse the forepart and shank portions of the bottom of the shoe, said shoe support comprising a shoe holder mounted for tipping movement about an axis extending laterally of the shoe in a location substantially adjacent to the bottom of the shoe to permit the forepart and shank portions of the shoe bottom to be presented with their longitudinal contours in substantially the same angular relation to the direction of the pressure applied by the roll. 80
17. In a machine of the class described, a leveling roll, a shoe support, and means for effecting relative movement of said roll and support lengthwise of the shoe to cause the roll to traverse the forepart and shank portions of the bottom of the shoe, said shoe support comprising a shoe holder mounted for tipping movement about an axis extending laterally of the shoe in such a location as to permit the bottom of the shank of the shoe at different portions of its length to be presented with its longitudinal contour in substantially perpendicular relation to the direction of the pressure applied by the roll. 85
18. In a machine of the class described, a leveling roll, a shoe support, and means for effecting relative movement of said roll and support lengthwise of the shoe to cause the roll to traverse the forepart and shank portions of the bottom of the shoe, said shoe sup- 90
- port comprising a shoe holder mounted for tipping movement about an axis extending laterally of the shoe and located substantially at the junction of the forepart and shank portions of the shoe bottom. 95
19. In a machine of the class described, a leveling roll, a shoe support, means for effecting relative movement of said roll and support lengthwise of the shoe to cause the roll to traverse the forepart and shank portions of the bottom of the shoe, said shoe support comprising a shoe holder mounted for tipping movement about an axis extending laterally of the shoe, and mechanism automatically operative in time relation to said relative movement of the roll and support to tip said holder about its axis for controlling the relation between the roll and the shoe. 100
20. In a machine of the class described, a leveling roll, a shoe support, and means for effecting relative movement of said roll and support lengthwise of the shoe to cause the roll to traverse the forepart and shank portions of the bottom of the shoe, said shoe support comprising a shoe holder mounted for tipping movement about an axis extending laterally of the shoe, and means automatically operative in time relation to said relative movement of the roll and support in the traverse of the roll from one end of the shoe toward the other end to tip said holder about its axis in opposite directions successively to control the relation between the roll and the shoe. 105
21. In a machine of the class described, a leveling roll, a shoe support, and means for effecting relative movement of said roll and support lengthwise of the shoe to cause the roll to traverse the forepart and shank portions of the bottom of the shoe, said shoe support comprising a shoe holder mounted for tipping movement about an axis extending laterally of the shoe and located substantially at the junction of the forepart and shank portions of the shoe bottom, and mechanism automatically operative to tip said holder in one direction about its axis when the roll is located at the ball of the shoe and thereafter to tip it in the opposite direction as the roll traverses the shank portion of the shoe. 110
22. In a machine of the class described, a leveling roll, a shoe support, and means for effecting relative movement of said roll and support lengthwise of the shoe to cause the roll to traverse the forepart and shank portions of the bottom of the shoe, said means being constructed to effect a pause in the relative movement of the roll and support when the roll is located at the ball of the shoe, said shoe support comprising a shoe holder mounted for tipping movement about an axis extending laterally of the shoe and located substantially at the junction of the forepart and shank portions of the shoe bottom, and mechanism automatically operative to tip the 115
- 120
- 125
- 130

holder about said axis at the time of said pause in the relative movement of the roll and support to present that portion of the shoe bottom that slopes rearwardly from the ball-line in substantially the same relation to the roll as the forepart previously operated upon.

23. In a machine of the class described, a leveling roll, a shoe support, and means for effecting relative movement of said roll and support lengthwise of the shoe to cause the roll to traverse the forepart and shank portions of the bottom of the shoe, said means being constructed to effect a pause in the relative movement of the roll and support when the roll is located at the ball of the shoe, said shoe support comprising a shoe holder mounted for tipping movement about an axis extending laterally of the shoe and located substantially at the junction of the forepart and shank portions of the shoe bottom, and mechanism automatically operative to tip the holder in one direction about said axis at the time of said pause in the relative movement of the roll and support to present that portion of the shank of the shoe adjacent to the ball-line in proper relation to the roll and thereafter to tip the holder in the opposite direction as the roll traverses the shank of the shoe to maintain different portions of the shank in substantially the same relation to the roll.

24. In a machine of the class described, a leveling roll, a shoe support, and means for effecting relative movements of said roll and support lengthwise of the shoe in opposite directions successively to cause the roll to traverse the forepart and shank portions of the shoe bottom repeatedly, said shoe support comprising a shoe holder mounted for tipping movement about an axis extending laterally of the shoe and located substantially at the junction of the forepart and shank portions of the shoe bottom, and mechanism automatically operative each time that the roll arrives substantially at the ball of the shoe to tip the holder about said axis for presenting that portion of the shoe bottom next to be operated upon in proper relation to the roll.

25. In a machine of the class described, a leveling roll, a shoe support, and means for effecting relative movements of said roll and support lengthwise of the shoe in opposite directions successively to cause the roll to traverse the forepart and shank portions of the shoe bottom repeatedly, said shoe support comprising a shoe holder mounted for tipping movement about an axis extending laterally of the shoe and located substantially at the junction of the forepart and shank portions of the shoe bottom, and mechanism automatically operative in time relation to the relative movement of said roll and support in each direction to tip the holder about said axis

in one direction while the roll is traversing the shank portion of the shoe and to tip it in the opposite direction when the roll is located substantially at the junction of the forepart and shank.

26. In a machine of the class described, a leveling roll and a shoe support relatively movable lengthwise of a shoe on said support to cause the roll to traverse the bottom of the shoe, and mechanism automatically operative in the traverse of the roll over the shank portion of the shoe bottom to tip the shoe progressively about an axis extending laterally of the shoe in such relation thereto as to maintain a substantially uniform angular relation between the direction of the leveling pressure and the longitudinal contour of the shank.

27. In a machine of the class described, a leveling roll and a shoe support relatively movable lengthwise of a shoe on said support to cause the roll to traverse the bottom of the shoe, and mechanism automatically operative in the traverse of the roll over the shank portion of the shoe bottom to tip the shoe progressively about an axis extending laterally of the shoe in a location substantially at the junction of the forepart and shank portions of the shoe bottom to maintain a substantially uniform angular relation between the direction of the leveling pressure and the longitudinal contour of the shank.

28. In a machine of the class described, the combination with a leveling tool, of a shoe support mounted for swinging movement to cause the tool to traverse the bottom of a shoe lengthwise of the shoe, and means for tipping the shoe in the leveling operation about an axis extending laterally thereof in a different location from the axis of movement of said support.

29. In a machine of the class described, the combination with a leveling tool, of a shoe support mounted for swinging movement to cause the tool to traverse the bottom of a shoe lengthwise of the shoe, said shoe support including a shoe holder mounted for swinging movement in the leveling operation about an axis extending laterally of the shoe in a location different from the axis of movement of the support as a whole for controlling the relation between the shoe and the tool.

30. In a machine of the class described, the combination with a leveling tool, of a shoe support mounted for swinging movement about an axis in a location remote from the shoe to cause the tool to traverse the bottom of the shoe lengthwise of the shoe, said shoe support including a shoe holder mounted for swinging movement about an axis extending laterally of the shoe and located substantially at the junction of the forepart and shank portions of the shoe bottom for controlling the relation between the shoe and the tool.

31. In a machine of the class described, a leveling tool, a shoe support mounted for swinging movement to cause the tool to traverse the bottom of a shoe lengthwise of the shoe, said shoe support including a shoe holder mounted for swinging movement about an axis extending laterally of the shoe in a different location from the axis of movement of the support as a whole, means for swinging the support, and mechanism automatically operative in time relation to the swinging of the support to swing the holder about its axis for controlling the relation between the shoe and the tool.

32. In a machine of the class described, a leveling tool, a shoe support mounted for swinging movement to cause the tool to traverse the bottom of a shoe lengthwise of the shoe, said shoe support including a shoe holder mounted for swinging movement about an axis extending laterally of the shoe and located substantially at the junction of the forepart and shank portions of the shoe bottom to control the relation between the shoe and the tool, means for swinging said support, and mechanism automatically operative in time relation to the swinging of the support in one direction to swing said holder about its axis in opposite directions successively.

33. In a machine of the class described, a leveling tool, a shoe support mounted for swinging movement to cause the tool to traverse the bottom of a shoe lengthwise of the shoe, said shoe support including a shoe holder mounted for swinging movement about an axis extending laterally of the shoe and located substantially at the junction of the forepart and shank portions of the shoe bottom to control the relation between the shoe and the tool, means for swinging said support, and mechanism automatically operative to swing the holder about its axis in one direction when the tool is located substantially at the junction of the forepart and shank portions of the shoe bottom and to swing it in the opposite direction progressively as the tool is traversing the shank portion of the shoe bottom.

34. In a machine of the class described, a leveling tool and a shoe support relatively movable to cause the tool to traverse the bottom of a shoe lengthwise of the shoe, said shoe support comprising a shoe holder mounted for swinging movement in the leveling operation about an axis extending laterally of the shoe in a location adjacent to the bottom of the shoe and adjustable to position shoes of different styles or sizes in substantially the same relation to said axis.

35. In a machine of the class described, a leveling tool and a shoe support relatively movable to cause the tool to traverse the bottom of a shoe lengthwise of the shoe, said shoe support comprising a shoe holder mount-

ed for swinging movement about an axis extending laterally of the shoe in a location substantially at the junction of the forepart and shank portions of the shoe bottom and having parts relatively adjustable heightwise and lengthwise of the shoe to position shoes of different styles or sizes with their bottom faces in substantially the same relation to said axis.

In testimony whereof I have signed my name to this specification.

ANDREW EPPLER.
